UNITED STATES PATENT OFFICE

THEODORE H. KRUEGER, OF DERBY, CONNECTICUT, ASSIGNOR TO BETTER PACKAGES INCORPORATED, OF SHELTON, CONNECTICUT, A CORPORATION OF NEW YORK

FEEDING AND MOISTENING GUMMED TAPE

Application filed October 1, 1929, Serial No. 396,447, and in Germany May 3, 1929.

The present invention relates to improvements for dispensing and moistening gummed tape, and more particularly it relates to that type of dispenser which provides for a roll of tape wound with the gummed side in and in which the roll is held in a cradle or basket without the use of a supporting spindle. In this form of device the tape after leaving the roll is reversed in its travel, is then fed beneath the roll support or cradle and is presented to the moisture applicator with the gummed side down.

In general, it is the object of my invention to provide a device of this type in which the following advantages among others will be realized: (1) a device which is compact and of low center of gravity; (2) a device in which the feed of the tape is facilitated by the pull thereof which serves partially to lift the roll from its supporting cradle and thereby diminishes the friction between the roll and its support, but when the pull stops and the lifting force on the roll ceases, the friction between the roll and cradle is increased and the increased friction effectively absorbs the momentum of the roll and prevents it from unwinding. (In prior tape dispensing devices where the roll of tape is mounted on a spindle, it is necessary to provide braking devices to overcome the momentum of the roll which greatly complicate the mechanism and provide a source of trouble by getting out of order); and (3) a device in which as stated the roll is wound with the gummed side in whereby the gum is protected against the atmosphere and the fingers and clothing of the operator or other persons.

More specific objects of the invention may be said to consist in the following:

1. To provide an improved guide means for the travel of the tape from the roll to the moisture applicator. In accordance with my invention, I provide, as far as possible, straight paths for the feed of the tape whereby the tendency of the tape when pulled to assume a straight line path may be satisfied. Where the path changes I provide

possible, preferably in the form of rollers. In this manner sharp bends which promote friction are obviated.

2. To provide means for guiding the tape which will permit of easy loading of the device, as by merely pushing the end of the tape of the roll through the guideways provided. I preferably accomplish this by providing, in addition to the rollers or pulleys mentioned, plates or lugs which form guideways which, while affording sufficient room for the tape to pass freely therethrough, nevertheless cause it to lie substantially flat, and prevent buckling of same. The stationary guide means is so arranged, however, that when the tape is pulled taut the latter will be substantially clear of the guides and extend unsupported from pulley to pulley.

3. To locate the pulley around which the tape first passes from the roll at the most advantageous position so that the direction of the feed of the tape will have the correct angle for diminishing the friction of the tape on the basket or cradle by the proper amount.

4. To provide an improved moistening device which includes means for compacting the bristles of a brush moistener to the end that the moistening operation may be efficiently and quickly performed and also to provide means permitting adjustment of the degree to which the bristles are compacted.

5. To provide an improved construction of the tape-cradle and guideways permitting same to be cheaply and easily manufactured and assembled.

In my prior Patent No. 1,567,655, dated December 29, 1925, a tape dispensing device was shown in which it was attempted to use a roll of tape similar to that of the present invention and in which the tape was fed from the roll through a guideway extending beneath the roll support. In the device shown in this patent, however, the above mentioned advantages were not realized for a number of reasons. One of these was that the curved guiding means shown therein afforded excessive friction to the travel of the tape by reason of the fact that

such curved guide opposed the natural tendency of the tape when pulled to straighten out.

Other objects and advantages will be apparent as the description proceeds and the novelty of the invention will be pointed out in the appended claims. The invention will be best understood by reference to the following detailed description thereof taken 10 with the accompanying drawings in which:

Figure 1 is a view in vertical, longitudinal section of a preferred embodiment,

Figure 2 is a view showing the roll of tape and manner in which it is unwound and 15 guided over the moistening device,

Figure 3 is a plan view with parts broken away,

Figures 4 and 5 are section views taken on lines 4-4 and 5-5 of Fig. 1, respectively, and

Figure 6 is a view showing the pressure and guide plate and the manner of securing the same in place.

In the drawings, 10 and 11 denote frame 25 members which constitute the sides of the device and which may conveniently be of cast metal, sides 10 and 11 being held together by means of bolts 12, 13, 14, etc. Contained within the frame members mentioned is a cradle for the roll of tape B, such cradle being composed of a member 15 of sheet metal, for example, which is secured to the frame members by means of lugs 18, 19, 20 and 21 on the under side thereof, and lugs 22, 22a, 23 and 24 on the upper side. Cradle 15 is designed so as to hold the roll of tape while making sufficient contact therewith so as to afford the proper amount of friction when the tape is unwound.

To unwind the tape, it is desirable to lead the tape upwardly as it leaves the roll for the purpose of reducing the friction of the roll against the cradle during the unwinding operation and so that when the pull of the tape is stopped, the full weight of the roll is borne by the cradle, thereby increasing the friction and preventing the roll from further rotating. Accordingly, the tape is led from the roll in an upward direction, as 50 shown, and a guideway therefor is provided, as follows: A roller 25 is journaled in the frame members 10 and 11 over which roller the free end A of the tape first passes. Below roller 25, preferably to the right thereof, as seen in Fig. 1, a second roller 26 is 55 journaled in frame members 10 and 11 together with a roller 27 to the right of the cradle 15 which is similarly journaled.

As stated a feature of the invention is that the guide means provided permit the end A of the tape to be threaded therethrough, beneath the rollers 26 and 27, merely by feeding the same at the left end of the frame. This is accomplished by providing a curved back and bottom plate 30 which is

held by the frame members 10 and 11 by means of flanges 32 cast therein, and right hand end 31 of which plate is held beneath a lug 32a cast in each frame member 10 and 11, and affording anchorage for the end of said plate 30 both in upward and outward directions, as shown. Co-operating with the bottom member 30 are plate-like flanges 34, 35 which extend horizontally from either frame member 10 or 11 and integral with lugs 20 and 19, respectively. It will be noted that the cradle and bottom members 15 and 30, respectively, serve also to hold the side members apart and in place by virtue of the bolts 12, 13 and 14. With reference to cradle member 15, it will be seen that it makes substantially line contacts with the roll B at three places. It will be seen further that the left hand portion in contact with lug 21, is of steeper slope than that in contact with lugs 18 and 19, the cradle being shaped so that a low point occurs adjacent such left hand portion. The result of this construction is to cause the tape to lie adjacent said left hand portion irrespective of the size of the roll whereby the angle at which the tape is fed off and around the roller 25 is constant within comparatively narrower limits thereby assuring that the friction of the roller in the support will be suitably varied by the pull of the end of the tape.

By means thus far described, the end of the tape may be accurately guided beneath rollers 26 and 27 in position for grasping above said roller 27. For the feeding of the tape from this point on, a roller 37 is provided which is journaled in frame members 10 and 11 so that the top of the roller conveniently is adjacent to the top of the said frame members.

It is also a feature of the invention that the location of roller 37 permits the feeding of the tape by the operator reaching his fingers in the space between said roller and the roll of tape B and pulling the tape by pressing it against the roller 37 and moving it forward so as to rotate said roller. It is to be noted that by virtue of the arrangement of the tape feeding and guiding means the tape is presented to the operator above the roller 37 with the gummed side down.

Having described the tape cradle and the means for guiding the feed of the tape therefrom, the moistening device may now be dealt with. It will be understood, however, that any other suitable form of moistening device than that illustrated may be used with the tape holding and guiding means above described.

Referring to Figs. 1 and 3, a well, preferably in the form of a casting 40, is secured to the end of frame members 10 and 11 by means of hook members at either side of said well, one of which 41 is seen in Fig. 1, such members engaging lugs on the frame

members, one of which 42 is also seen in Fig. 1. Contained in the well 40 between the end wall thereof and a lug 44 is a brush 45 for feeding water contained in the well to the gummed side of the tape, brush 45 having the bristles thereof projecting above the top of the well, as shown. For the purpose of maintaining the proper compression of the bristles, and thereby the proper feed of the water to the tape, the same are squeezed slightly between a cover member 47 of said well, and the edge, preferably slightly upturned, as shown, of a table 48 which lies upon the ends of the frame members 10 and 11 as well as on top of the well 40. Cover plate 47 has depending lugs 47a as shown which have curved ends and by means of which by tilting the cover somewhat the pressure on the bristles of brush 45 may be varied as shown in dot and dash lines Fig. 1. Movement of the table 48 away from the brush is prevented by vertical walls formed by the termination of the flanges 49 and 50 of the frame members 10 and 11, respectively, and movement sideways, of the frame members by means of shoulders 51 engaging behind said flange members 49 and 50 all as shown in Figs. 3 and 6. A top guide and locking member is formed by a clip 53 which is placed over the tape on the table 48 and has ends engaging the sides of the frame members and is held securely to said members by means of lugs 54 and 55 which project through slots in the ends of the clip, which, due to the springy nature of the metal thereof, snaps over said lugs and locks the well 40 to the frame members 10 and 11. Clip 53 is also provided with a cutting edge 56, preferably saw-toothed, against which the tape is cut, after the desired length has been pulled over the wet brush by the operator. Upon removal of cover 47, the brush may be tilted forward and removed without disturbing the guide. The device is conveniently provided with base lugs 57, etc., around which rubber washers 58 may be placed, whereby the device is prevented from sliding, due to the pulling of the tape, or from other causes. The loading of the machine and the threading of the tape through the machine is accomplished as follows: The paper roll B is laid into cradle 15. The free end of the tape strip A is then grasped by the operator who passes it over roller 25 and tucks or pushes it downward between roller 25 and the rear wall of the base plate 30 whereby the strip is threaded between roller 26 on one side and base plate 30 on the other side, from there on it passes between flanges 34 and 35 on one side and base plate 30 on the other side, then between guide roller 27 and base plate 30 and finally projects out over roller 37. The operator then inserts it through the slit between plate 48 and

clip 53. During the threading of the strip into the straight chute formed on one side of the strip by flanges 34 and 35 and on the other side by base plate 30 the buckling of the paper, which might occur due to its being threaded or pushed from behind is prevented by the fact that the space between these lugs 34 and 35 and base plate 30 is so small that the strip is held almost flat during its passage through the chute. 75

Furthermore, due to the fact that the gummed side of the tape is down, any tendency of the tape to curl laterally does not result in the end of the tape striking lugs 34, 35. Instead, such curled portions merely hug the bottom member 30. 80

In feeding out a desired length of strip whose front edge at the beginning of the operation is located immediately under the cutting edge 56, the operator presses the tape with his finger against roller 37 and then revolves the roller, drawing the tape forward with it. The front edge of strip A is thereby advanced far enough beyond the slit between plate 48 and clip 53 so that 85 the end which now projects over the water tank can be grasped (see Fig. 1). Grasping this free end of strip A the operator now pulls on it until he has withdrawn the desired length of strip whereupon he cuts 90 or tears it off against the cutter edge 56 with an upward motion of the hand. 95

Whenever the operator in this manner feeds the tape this pulling on one end of the strip together with the inertia of the paper 100 roll B and the friction between roll B and cradle 15 causes the intervening length of tape to be drawn taut. This drawing taut of the strip causes it to assume the shortest possible path, namely a straight path, in passing from one guide roller to the next guide roller, for instance, from roller 26 to roller 27 and therefore when the strip is drawn taut there is no substantial contact or friction between the strip and base plate 30 105 or between the strip and flanges 34 and 35. The use of guide rollers therefore makes possible a straight and extremely thin or shallow chute 30, 34 and 35, the thinness of the chute having the great advantage of 110 holding the tape almost flat during the initial threading operation thereby preventing buckling of the strip when it is pushed into the chute from behind; the straightness of this chute preventing friction on the strip 115 when it is later pulled taut from the exit end of the machine. 120

As soon as strip A is drawn taut it exerts components of force on supply roll B tending to lift roll B against the force of gravity, this being due to the particular location of roller 25. This and the momentum which roll B develops once it is in motion decreases the resistance to the forward pull on strip A. However, the instant the forward pull 125 130

on strip A ceases, as when the strip is cut off against saw blade 56, the frictional resistance which hinders the forward motion of strip A is greatly increased because 5 there is no longer any lifting action exerted against roll B and because the momentum of roll B is stopped by its friction with cradle 15. Thus the weight of the roll acts as its own brake, which prevents the momentum 10 of the roll from unwinding more paper than is desired, and it accomplishes this braking action without any additional mechanism such as friction plates or tension springs on the side of the paper roll which would have 15 to be used if the roll B were mounted so as to turn on a spindle extending through its center. Aside from other disadvantages, extra braking devices such as are necessary with a spindle mounting have the great fault 20 of continuing their braking action not only after the feeding pull of the tape but also during the entire feeding operation.

While I have described my preferred embodiment in detail, it will be understood that 25 various changes may be made therein within the scope of my invention, and that parts thereof may be used without others. I also desire to point out that while many advantages of my device will be sacrificed, it is 30 nevertheless possible to use it without modification for containing and moistening tape which is wound on the outside in circumstances in which this is the only form of tape available.

I claim:

1. A tape dispensing device comprising a pair of frame members, a supporting member for a roll of tape, a bottom member beneath said supporting member and rollers 40 around which said tape is guided, said frame members having lugs for holding said supporting and said bottom members and having journals for said rollers and bolts for holding said frame members together 45 against said supporting and bottom members.

2. In a tape dispensing device, a support for a roll of tape comprising a member of generally concave shape in the nature of a 50 cradle, a guide member around which the tape passes as it is fed from said roll, said support having a portion adjacent said guide which is steeper than the remaining portions thereof, whereby the lowest point 55 is adjacent the end of said portion first mentioned and said roll is caused to gravitate to a position against said first mentioned portion irrespective of the size of the roll.

3. A strip serving device of the "pull out" type in which a roll of gummed tape wound with the gummed side in is disposed 60 within a tape basket, and which affords means whereby a desired length of moistened tape may be withdrawn, characterized 65 by a feeding mechanism for said tape hav-

ing guiding elements which permit the tape to be fed from a point behind and above the bottom of the roll, thence downwardly and beneath the tape basket and then upwardly to the point of delivery of the tape 70 above the bottom of said roll, such guiding elements comprising four guide rollers at the turns respectively of said tape and a stationary guide beneath said basket disposed sufficiently close to the bottom of the basket as to permit the end of the tape to be pushed from behind during the loading operation without buckling but offering substantially no interference to the feed of the tape when pulled. 75

4. A strip serving device of the "pull out" type in which a roll of gummed tape wound with the gummed side in is disposed within a tape basket, and which affords means whereby a desired length of moistened tape may be withdrawn, characterized by having a frame adapted to rest upon a table or other supporting surface and containing the tape basket which is disposed close to the bottom of the frame but affording a space between the basket and the bottom of the frame sufficient to permit passage of the tape therebetween, whereby the center of gravity of the device is low, and by feeding mechanism comprising anti-friction guiding elements permitting the tape to be fed from a point behind and above the bottom of the roll thence downwardly beneath the basket and then upwardly to the point of delivery of the tape above the bottom of said roll, and guide ways 90 between said elements serving to guide the feed of the tape and to prevent buckling when pushed in from behind during the loading operation, but offering substantially no interference to the feed of the tape caused by pulling the end thereof, said anti-friction guiding elements being disposed so as to provide straight line paths 95 of travel between said elements of the tape when pulled. 100

5. In a strip serving device of the "pull out" type in which a roll of gummed tape wound with the gummed side in is disposed in a tape basket and which affords means whereby a desired length of moistened tape may be withdrawn, a feeding mechanism comprising anti-friction guiding elements 115 permitting the tape to be fed from a point behind and above the bottom of the roll, thence downwardly beneath said tape basket and upwardly to the point of delivery of the tape above the bottom of said roll, and guide ways between said elements serving to guide the feed of the tape and prevent buckling thereof when pushed in from behind during the loading operation but offering substantially no interference to the feed of the tape caused by pulling the end thereof, said anti-friction guiding elements 120 125 130

being disposed so as to provide straight line paths of travel between said elements for the tape when pulled.

6. In a strip serving device of the "pull out" type in which a roll of gummed tape wound with the gummed side in is disposed within a tape basket and which affords means whereby a desired length of moistened tape may be withdrawn, a feeding mechanism for said tape comprising rollers permitting the tape to be fed from a point behind and above the bottom of the roll, thence downwardly beneath said basket and upwardly to the point of delivery of the tape 10 above the bottom of said roll, and guide ways between said rollers serving to guide the feed of the tape and to prevent buckling thereof when pushed in from behind during the loading operation but offering substantially no interference to the feed of the tape 15 caused by pulling the end thereof.

7. A strip serving device of the "pull out" type in which a roll of gummed tape wound with the gummed side in is disposed 20 within a tape basket, and which affords means whereby a desired length of moistened tape may be withdrawn, characterized by having a frame adapted to rest upon a table or other supporting surface and containing the tape basket which is disposed 25 close to the bottom of the frame but affording a space between the basket and the bottom of the frame sufficient to permit passage of the tape therebetween, whereby the 30 center of gravity of the device is low, and by feeding mechanism comprising anti-friction guiding elements permitting the tape to be fed from a point behind and above the bottom of the roll, thence downwardly beneath 35 the basket and then upwardly to the point of delivery of the tape above the bottom of said roll.

In testimony whereof I have affixed my signature to this specification.

40 THEODORE H. KRUEGER.
